UNITED STATES PATENT OFFICE.

WILLIAM L. ROSS, OF JERSEY CITY, NEW JERSEY.

TOOL-CLAMP.

1,350,240.

Specification of Letters Patent. Patented Aug. 17, 1920.

Application filed September 11, 1917. Serial No. 190,829.

To all whom it may concern:

Be it known that I, WILLIAM L. Ross, a citizen of the United States, residing at Jersey City, in the county of Hudson and State of New Jersey, have invented new and useful Improvements in Tool-Clamps, of which the following is a specification.

This invention relates to tool clamps and more particularly to a clamp for drills, the 10 same being designed for a number of uses and being intended to take the place of a number of clamps of different forms. The primary object of the invention is the provision of a clamp of this character which 15 may be expanded or contracted and locked in its several positions.

Another object of the invention is the provision of a clamp of this character which comprises a pair of (L) shaped members ad- 20 justably connected together in such a manner that the horizontal portions may be radially adjusted with relation to each other for a number of uses.

A still further object of the invention is 25 the provision of a device of the character described which is of simple construction, inexpensive to manufacture and thoroughly reliable and efficient for the purpose for which it is intended.

30 With these and other objects in view, the invention resides in the novel combination and arrangements of parts fully described in the following description, particularly pointed out in the appended claim and 35 shown in the accompanying drawing in which—

Figure 1 is a side elevation of the clamp showing one of its uses.

Fig. 2 is a vertical sectional view there- 40 through and

Fig. 3 is a horizontal section on the line 3—3, of Fig. 2.

Referring to the drawing by characters of reference, A, designates an ordinary work 45 bench or table and B, a hand drill, which is supported in working position with relation to the work C, by means of the clamp designated generally by D. The clamp comprises a pair of angle members, one being in 50 the nature of a foot indicated by the numeral 10 and the other being in the nature of

a head and indicated by the numeral 11. The horizontal portion of the foot member 10 is provided with an opening 13 through which passes a bolt 12, the said bolt also 55 passing through the bench or table A.

The bolt 12, is threaded at its lower extremity for the reception of a nut 14. The vertical limbs of the members 10 and 11, are interiorly threaded as at 15, to receive the 60 threaded extremities 16, of the connecting rod 17, which is provided with a manipulating portion 18. Lock nuts 19, have threaded engagement with the rod 17, to retain the members 10 and 11, in their ad- 65 justed positions.

In use of the device as shown, the drill is placed in operative position against the work and the clamp (D), is adjusted to secure the same in place by drawing the members 10 70 and 11, toward each other. It is sometimes found desirable to adjust the horizontal limbs of the members 10 and 11, at different angles with relation to each other and this is accomplished by turning the same to the 75 position desired and locking them in their adjusted position through the medium of the nuts 19, thus accommodating the clamp to many uses whereas it now requires a sepa- 80 rate clamp for each use.

What is claimed as new is:—

The combination with a bench or like support; of means thereon for holding and advancing a drill to its work, comprising an angle foot member and an angle head mem- 85 ber which is disposed thereabove, pivot means securing the foot member to the bench or support, binding means for said pivot means, the vertical legs of the respec- 90 tive head and foot members having bores one provided with right hand threads and the other with left hand threads, a bolt member having a central manipulating portion and a shank provided with right and left hand threads respectively from said manipulating 95 portion and received in and engaging with the right and left hand threads in the legs of the said foot and head members, and lock nuts on the bolt contacting with the confronting ends of the said legs. 100

In testimony whereof I affix my signature.
WILLIAM L. ROSS.
